UNITED STATES PATENT OFFICE.

HERBERT E. KEELER, OF NEW YORK, N. Y., ASSIGNOR TO CURTAIN SUPPLY COMPANY, OF CHICAGO, ILLINOIS, A CORPORATION OF NEW JERSEY.

CURTAIN-FIXTURE.

No. 919,180.

Specification of Letters Patent.

Patented April 20, 1909.

Application filed April 11, 1903. Serial No. 152,152.

To all whom it may concern:

Be it known that I, HERBERT E. KEELER, a citizen of the United States, and resident of New York city, in the county and State 5 of New York, have invented certain new and useful Improvements in Curtain-Fixtures, of which the following is a specification, taken in connection with the accompanying drawings, which form a part of 10 the same.

This invention relates to curtain fixtures and relates more especially to such curtain fixtures as are employed in railway cars and which serve to securely hold a spring- 15 actuated curtain in any desired position.

In the accompanying drawings in which the same reference character refers to similar parts in the several figures, Figure 1 is a front view partly in section showing one 20 embodiment of this invention as applied to a curtain. Fig. 2 is a detail view on a large scale showing one form of foot used in this curtain fixture in connection with the co-operating guideway. Figs. 3, 4 and 5 are 25 similar views showing other forms of foot.

In the embodiment of this invention shown in the drawings the two posts on either side of the window are shown as provided with suitable grooves or guide- 30 ways A with which the curtain fixture co- 35 operates.

The curtain C is secured to a spring roller B of the usual construction which is preferably constantly acting and which is mounted 40 in suitable bearings at the top of the window.

The curtain tube D which may be formed of metal and which serves to hold the curtain firmly in position by allowing the use 45 of a strongly acting spring roller, is firmly fastened in the curtain, preferably in a pocket near the bottom of the same and the two shoes E are mounted in the ends of the tube and are preferably accurately guided 50 therein so as to reciprocate transversely of the curtain. These shoes are also preferably spring-pressed outward into co-operation with the guideways. Suitable guiding members are mounted in the shoes for engagement with the guideways to secure the alinement of the curtain as it is moved up and down, and also to hold it firmly in position.

As indicated in Fig. 1, the shoes E are rigidly secured to the plungers F which fit within the curtain tube and are formed of 55 such length as to be guided therein during the operation of the fixture. The inner end of each plunger is preferably engaged by the spiral spring T which engages a suitable stop R in the curtain tube. Any desired 60 means may be employed for securing the proper reciprocation of the plunger and for holding it properly within the curtain tube. A screw O is indicated passing through a suitable slot in the tube and engaging the 65 spindle which allows a limited reciprocating movement of these parts. It is not necessary, however, that the shoes be mounted upon the curtain in this particular manner, although the shoes should be mounted to 70 reciprocate properly for coöperation with the guideways.

In each of the shoes separated guiding members are mounted for engagement with the guideways and are preferably formed 75 to produce a proper holding action so as to maintain the curtain in position. These guiding members preferably comprise an irregularly rotating guiding member mounted in the upper portion of the shoe, this 80 guiding member preferably operating in connection with another guiding member mounted in a lower position in the shoe. As indicated in Fig. 2, the irregularly rotating guiding member H may be in the form of a 85 guide roll which is preferably formed with a suitably roughened periphery to positively engage the guideway and to prevent slip with respect thereto. The distance of the portion of the periphery of the guiding 90 member which is in contact with the guideway from the axis of the guiding member varies as the guiding member rotates irregularly through contact with the guideway. The irregular rotation of this guiding member 95 may be secured by mounting it upon the eccentrically placed pivot K in the shoe, as is seen in Fig. 2 so as to form an eccentric guideroll as indicated. This irregular rotation as will be seen forces the plunger 100 of the shoe inward against the spring pressure upon it as the shoe is moved along the guideway and this spring pressure in a readily understood manner tends to prevent

the rotation of this irregularly rotating guiding member and tends to hold the curtain in position. Another coöperating guiding member is preferably employed in the 5 shoe for engagement with the guideway. In the form of foot indicated in Fig. 2, this guiding member which is there shown at the lower end of the shoe is in the form of a pivoted guideroll mounted in the shoe, although it is understood that it is not necessary that this coöperating guiding member be rotary. It may take the form indicated in Fig. 3 in which the sliding guiding member L is indicated as coöperating with the 10 irregularly rotating guiding member K which is separated therefrom. By placing the irregularly rotating guiding member nearer the spring roller than the other co-operating guiding member, a very desirable 15 action of the curtain takes place, since under these conditions the holding action of the curtain fixture is reliable and it operates smoothly as it is moved along the guideways, it is not of course necessary that the unsymmetrical forms of shoe such as are shown 20 in Figs. 2, 4 and 5 be always used so that the irregularly rotating guiding member is in that end of the shoe which is uppermost.

Shoes formed with several coöperating 25 guiding members used in connection with an irregularly rotating guiding member may be employed in this curtain fixture. In Fig. 3, the shoe E is indicated secured to the plunger F which may be mounted in the 30 curtain tube, as has been described and an irregularly rotating guiding member H is shown which may be mounted in the shoe to rotate about the pivot K. Separated co-operating guiding members may be used on 35 either side of this irregularly rotating guiding member. These coöperating guiding members may take the form of the guiderolls I I¹ which rotate smoothly about their pivots and are preferably only lightly in 40 engagement with the guideway in the position indicated. The irregularly rotating guiding member may be mounted nearer the plunger G of the shoe as indicated in Fig. 4 in which the irregularly rotating guiding 45 member H rotates with respect to its pivot K which is adjacent the plunger, as indicated. A coöperating guiding member is preferably employed separated from and below the irregularly rotating guiding member and this coöperating guiding member 50 may take the form I as indicated.

Those familiar with this art may make 55 many changes in the form, proportion and numbers of parts of this curtain fixture without departing from the spirit of this invention or losing the advantages of the same. Furthermore, parts of this invention may be employed without using all of the same and may be employed in connec-

tion with other devices without departing 65 from this invention. I do not, therefore, desire to be limited to the disclosure which has been made in this case, but

What I claim as new and what I desire to 70 secure by Letters Patent is set forth in the appended claims.

1. In a curtain fixture, a spring-actuated curtain, guideways adjacent said curtain, a curtain tube mounted at the lower end of said curtain, shoes having plungers secured 75 thereto to coöperate with said guideways, said plungers fitting within said tube and being spring-pressed outward, irregularly rotating guiding members mounted in said shoes adjacent said plungers to engage said 80 guideways and coöperating guiding members in said shoes below said irregularly rotating guiding members.

2. In a curtain fixture, a spring-actuated curtain, guideways adjacent said curtain, spring-pressed shoes secured to said curtain to coöperate with said guideways, said shoes being provided with irregularly rotating 85 guiding members, each of said irregularly rotating members being formed with a periphery the distance of the portion of which 90 is in contact with said guideway from the axis of said guiding member varies as said guiding member is rotated and dissimilar co-operating guiding members mounted in said 95 shoes below said irregularly rotating guiding members.

3. In a curtain fixture, a guideway, a shoe to coöperate with said guideway, said shoe having an irregularly rotating guiding 100 member mounted therein to engage said guideway, the distance of the portion of the periphery of said guiding member in contact with said guideway from the axis of 105 said guiding member varying as said guiding member is rotated and a separated coöperating regularly rotating guideroll mounted in said shoe to engage said guideway.

4. In a curtain fixture, a curtain stick, 110 shoes mounted on said curtain stick and spring-pressed outward to coöperate with guideways, an irregularly rotating guiding member in each of said shoes and a dissimilar separated coöperating guiding member 115 in each of said shoes to engage said guideways, said irregularly rotating guiding members tending to angularly tilt said shoes as they move along said guideways.

5. In a curtain fixture, a spring-actuated 120 curtain, spring pressed shoes mounted on said curtain to coöperate with guideways, each of said shoes having an irregularly rotating guiding member mounted therein to engage said guideways, the distance of 125 the portion of the periphery of said guiding member in contact with said guideway from the axis of said guiding member varying as

said guiding member is rotated and a dissimilar separated coöperating guiding member mounted in said shoe to engage said guideway, said irregularly rotating guiding members tending to angularly tilt said shoes as they move along said guideways.

6. In a curtain fixture, a shoe to coöperate with a guideway, said shoe comprising a single eccentric guide roll to engage said

guideway and to be rotated thereby and a dissimilar separated coöperating guiding member to engage said guideway, said eccentric guiding roll tending to angularly tilt said shoe as said guide roll rotates.
